MEANS FOR SECURING IDENTIFICATION TAGS

Charles Doppelt, Chicago, Ill.

Application March 13, 1944, Serial No. 526,279

4 Claims. (Cl. 40—20)

This invention relates to the means for securing identification tags to luggage and the like.

One of the objects of this invention is to provide a holder for identification tags which can be easily and quickly applied, which cannot be accidentally disconnected and which is economical to manufacture.

Another object is to provide a holder for identification tags so that the fastening elements when same is applied are not exposed, that is, they are positioned inside the loop, thus presenting a smooth outside surface which is devoid of projecting parts, with only the fabric of the holder exposed. This will prevent any accidental loosening or detachment of the tag.

Other objects will become apparent as this description progresses.

In the drawing:

Fig. 1 is a perspective view showing an identification tag secured to a bag by means of my securing means.

Fig. 2 is a front plan view showing the tag and my securing means.

Fig. 3 is a perspective view showing my securing means detached, and,

Fig. 4 is a cross-sectional view taken on line 4—4 of Fig. 2.

The conventional identification tag 10 is secured to the handle 12 of a traveling bag by means of my attaching means, generally indicated at 14. The attaching means 14 comprises a strap 16 made of leather or the like, which terminates in a wider section 18 at one end thereof. Permanently secured to said section is the stud or male member 20 of a conventional snap fastener. The female member 22 is secured to the opposite end of the strap 16.

In the section 18 and on the opposite sides of the stud 20, I provide a pair of transverse slots 24 and 26, parallel to each other.

As best shown in Fig. 4, in securing the tag, the end of the strap carrying the female member 22 is passed through the slot 24 in the tag 10, then through the slot 26 from the inside, then over the exposed or outside 20a of the stud 20 to cover same, then through the slot 26 and is reversely bent as at 28 for securement as at 30. The strap thus forms a complete loop with the exposed portion 22a of the female member 22 positioned inside or within the loop. Thus the snap fasteners are completely covered when the securing means are attached and a smooth surface is presented throughout with no projecting

parts that can be accidentally engaged to unsnap the fasteners. Nor will the snap fasteners be disengaged by any pull on the tag 10, for the passing of the strap through the two slots 24 and 26 and reversely bending same for securement takes up the pull or strain that would otherwise be transmitted to the snap fasteners. The fastener will therefore not be accidentally disengaged or disengaged by any pull on the tag, but only by directly unfastening same if desired.

It will be understood that various changes and modifications can be made without departing from the spirit and scope of the appended claims.

I claim:

15 1. In a structure of the character described comprising a strap, the female member of a snap fastener secured to one end of said strap and the male member to the other end, said strap having a slot on each side of the male member, the other 20 end of said strap passing through said slots and reversely bent with said two members snapped in locking position.

2. In a structure of the character described comprising a strap having the male and female 25 members of a snap fastener, each secured to the opposite ends of the strap, a pair of slots parallel with each other and transversely of said strap on the opposite sides of one of said members, the other end of said strap passing through the slots 30 and reversely bent with said two members snapped in locking position.

3. In a structure of the character described comprising a strap passing through an identification tag, the members of a snap fastener, each secured to the opposite ends of the strap, said strap having a pair of slots on the opposite sides of one of said fastening members with the other end passing through said slots and reversely bent and secured to said fastening member within the 40 strap loop.

4. In a structure of the character described comprising a strap secured to an identification tag, the members of a snap fastener each secured to the opposite ends of the strap, said strap 45 having a pair of slots on the opposite sides of one of said fastening members with the other end of the strap passing outwardly through said outermost slot and over the exposed portion of the snap member and inside through said other slot and reversely bent for securement to said snap fastener.

CHARLES DOPPELT.
